(57) **CLAIM**

What is claimed is the ornamental design of a stacking armchair, as shown and described.

DESCRIPTION

FIG. 1 is a frontal perspective view of the stacking armchair showing my new design;

FIG. 2 is a right elevational view thereof;

FIG. 3 is a front elevational view thereof;

FIG. 4 is a bottom plan view thereof;

FIG. 5 is a top plan view thereof; and,

FIG. 6 is a rear elevational view thereof.

The broken lines in the drawings illustrate the portions of the

design that form no part of the claim.
